UNITED STATES PATENT OFFICE.

JOHN S. PADON, OF WESTPLAINS, MISSOURI, ASSIGNOR OF ONE-HALF TO
JOSEPH L. VAN WORMER, OF WESTPLAINS, MISSOURI.

SEWING-AWL.

SPECIFICATION forming part of Letters Patent No. 695,885, dated March 18, 1902.

Application filed September 20, 1901. Serial No. 75,754. (No model.)

To all whom it may concern:

Be it known that I, JOHN S. PADON, a citizen of the United States, residing at West-
plains, in the county of Howell and State of
Missouri, have invented a new and useful
5 Sewing-Awl, of which the following is a speci-
fication.

This invention relates to sewing-awls, and
has for its object to provide an improved hand-
10 operated device of this character which is
especially adapted for use in sewing leather
and in which the thread is always exposed to
view, so that the operator may readily deter-
mine the amount of thread which is carried
15 by the awl.

It is furthermore designed to facilitate the
application and removal of the needle and
also to provide for rotatably mounting the
20 thread-carrying spool upon the exterior of
the handle of the awl and adjacent to the
base of the needle, so that the thread may be
conveniently engaged with the needle and also
effectively fed thereto.

A further object is to employ common fas-
25 tening means for connecting the needle to the
handle of the awl and for preventing dis-
placement of the thread-spool, thereby to re-
duce the number of parts of the device, so as
30 to materially simplify the same, and also to
facilitate the application and removal of the
needle and the thread-spool.

A final object is to provide simple and ef-
ficient means for guiding the thread from the
35 spool, so as to prevent tangling thereof, and
also to arrange said guiding means to coöp-
erate with the thumb or one of the fingers of
the operator for the purpose of placing the
desired tension upon the thread, thereby to
obviate too rapid feeding of the latter.

40 With these and other objects in view the
present invention consists in the combination
and arrangement of parts, as will be here-
inafter more fully described, shown in the
accompanying drawings, and particularly
45 pointed out in the appended claims, it being
understood that changes in the form, propor-
tion, size, and minor details may be made
within the scope of the claims without depart-
ing from the spirit or sacrificing any of the
50 advantages of the invention.

In the drawings, Figure 1 is a perspective

view of a sewing-awl embodying the pres-
ent invention. Fig. 2 is a central longitu-
dinal sectional view thereof. Fig. 3 is a de-
tail perspective view of the thread-carrying 55
spool. Fig. 4 is a detail perspective view of
the plate for supporting one end of the thread-
guide.

Similar characters of reference designate
corresponding parts throughout the several 60
figures of the drawings.

Referring to the accompanying drawings,
1 designates a common or ordinary form of
wooden awl-handle, which has its forward
and enlarged end provided with a cylindrical 65
reduced stem portion 2, into which is longi-
tudinally driven the shank 3 of a needle-
clamp embodying a plurality of externally-
screw-threaded clamping-jaws 4, which pro-
ject outwardly beyond the handle. These 70
clamping-jaws are formed by splitting the
outer end of the shank 3 in a common and
well-known manner.

Upon the reduced stem portion 2 there is
rotatably fitted a thread-carrying spool 5, 75
which is provided with opposite end flanges 6
and also having a tongue 7, to which one end
of the thread 8 is connected, said thread being
wound upon the spool in the usual manner.

A circular plate or washer 9 is loosely fitted 80
upon the projected portions of the jaws 4 and
lies against the outer end of the stem 2, there
being a clamping-nut 10 fitted to the screw-
threaded portion of the jaws and bearing
against the plate 9, so as to hold the same in 85
place, and thereby prevent outward endwise
displacement of the spool. One or more wash-
ers 11 may be interposed between the plate 9
and the nut 10. An ordinary form of grooved
needle 12, having an outer terminal eye, has 90
its angular shank portion clamped between
the jaws 4, so as to be replaced whenever de-
sired, whereby the nut 10 has the double func-
tion of preventing displacement of the spool
and also of holding the needle to the handle. 95

For guiding the free end of the thread as
it passes from the spool to the eye of the nee-
dle, through which it is threaded in the usual
manner, there is provided a flat metallic strip
13, which has one end secured to the forward 100
end portion of the handle 1, as indicated at
14, and projected outwardly therefrom across

- the flanges of the spool, the outer end of the strip being provided with a lateral head or projection 15, which snugly engages the outer side of the adjacent edge portion of the plate 5 9, the latter having a seat for the reception of the outer end portion of the strip, preferably formed by a pair of projections 16, which snugly embrace the strip and prevent lateral movement thereof. The intermediate portion 10 of the guide-strip is provided with a perforation 17, through which the thread passes in an outward direction from the spool.
- From the foregoing description it will be seen that the spool is located at or adjacent 15 to the base of the needle, whereby the thread has a comparatively short distance to travel from the spool to the needle, thus materially reducing the liability of the thread to become tangled. Moreover, the spool is always exposed 20 to view, so that the amount of thread on the spool can be readily observed.
- In the operation of the device the thumb or one finger is placed against the outer side of the thread-guide and over the perforation 25 therein, thereby to clamp the thread between the guide and the finger, so as to place a tension thereon, and thereby obviate too rapid feeding of the thread without employing springs or other complicated tension devices.
- Having thus described my invention, what I claim as new, and desire to secure by Letters Patent, is—
1. A sewing-awl, comprising a handle having a needle-holder at one end thereof, and a thread-spool mounted externally upon said end of the handle and in substantially longitudinal alinement with the needle-holder.
  2. A sewing-awl, comprising a handle having one end provided with a cylindrical stem, a needle-holder carried by the outer end of the stem, and a rotatable thread-spool mounted upon the stem in rear of the needle-holder and in substantially longitudinal alinement therewith.
  3. A sewing-awl, comprising a handle having one end provided with a reduced cylindrical stem, a needle-holder carried by the outer end of the stem, and a rotatable thread-spool mounted upon the stem and in substantially longitudinal alinement with the needle-holder.
  4. A sewing-awl, comprising a handle, needle-holding jaws projected at one end of the handle, a clamping device embracing the 55 jaws, and a thread-spool mounted externally upon the handle and in substantially longitudinal alinement with respect to the needle-holding jaws, the clamping device also forming means to prevent outward displacement 60 of the spool.
  5. A sewing-awl, comprising a handle, a plurality of externally-threaded needle-clamping jaws carried by and projected at one end of the handle, a thread-spool mounted externally 65 upon said end of the handle and located inwardly from and in substantially longitudinal alinement with respect to the projected

jaws, and a clamping-nut detachably fitted to the jaws and also forming means to prevent endwise displacement of the spool.

6. A sewing-awl, comprising a handle, a thread-spool mounted externally at one end thereof, means to prevent outward displacement of the spool and located at the outer end thereof, a thread-guide having its opposite ends supported upon the handle and the said means, and also provided with an intermediate perforation for the reception of the thread, and a needle-holder carried by the spool end of the handle.

7. A sewing-awl, comprising a handle, a thread-spool mounted at one end thereof, a stop device located at the outer end of the spool to prevent displacement thereof, and also provided with a seat, and a thread-guide 85 having one end connected to the handle and its opposite end received within the seat of the stop device, the intermediate portion of the guide being provided with an eye for the reception of the thread.

8. A sewing-awl, comprising a handle, a thread-spool mounted upon one end of the handle, a washer carried by the outer portion of said end of the handle to prevent displacement of the spool and provided with an edge 95 notch or seat, and a thread-guide having one end secured to the handle and its opposite end received within the seat of the washer and also provided with a lateral projection engaging across the outer side of the washer, the intermediate portion of the guide bridging the spool and provided with an eye for the reception of the thread.

9. A sewing-awl, comprising a handle having one end provided with a reduced stem, a 105 thread-spool rotatably mounted upon the stem, externally-screw-threaded needle-holding jaws projected longitudinally from said end of the handle, a washer embracing the base of said jaws and provided with an edge notch or seat, 110 a clamping-nut applied to the threaded portions of the jaws, and a thread-guide having its inner end secured to the handle and its opposite end received within the notch or seat of the washer, and also provided with a 115 lateral projection engaging the outer side of the washer, the intermediate portion of the guide bridging the spool and provided with a perforation for the reception of the thread.

10. A sewing-awl, comprising a handle, an 120 external rotatable thread-spool mounted upon the handle, and needle-holding means carried by one end of the handle and forming means to prevent accidental endwise displacement of the spool, the latter being disposed concentrically with respect to the needle-holding means.

In testimony that I claim the foregoing as my own I have hereto affixed my signature in the presence of two witnesses.

JOHN S. PADON.
